UNITED STATES PATENT OFFICE.

ERIC HEDBURG, OF KINGMAN, ARIZONA.

LINING FOR BALL MILLS.

Application filed April 5, 1920. Serial No. 371,291.

To all whom it may concern:

Be it known that I, ERIC HEDBURG, a citizen of the United States, residing at Kingman, in the county of Mohave and State of 5 Arizona, have invented certain new and useful Improvements in Linings for Ball Mills, of which the following is a specification.

This invention relates to linings for ball 10 mills and it consists in the novel features hereinafter described and claimed.

In one form of the invention it is the object to provide a lining especially adapted to be used in a mill which discharges the 15 material at the peripheral portion thereof. In the other form of the invention it is the object to provide a lining for a mill which discharges the material at the center thereof.

In both forms of the invention the lining 20 is made in sections or segments of a circle whereby new and unused sections may be placed in the mill as the original sections become worn and hence the material which is passed through the mill is ground or dis- 25 integrated to a uniform degree. In both forms of the invention the lining sections are provided with grooves in which the balls are adapted to travel and with which the balls cooperate during the grinding opera- 30 tion.

In the preferred form of the invention the lining sections are mounted upon feet whereby the body portions of the sections are spaced from the inner surface of the 35 drum or body of the mill. These sections are further provided with transversely disposed slots or recesses through which the ground material may pass thus separating the same promptly from the coarser ma- 40 terial. In this form of the invention the discharge end of the mill is provided with gate controlled apertures through which the ground material may pass from the drum or body of the mill.

45 In the accompanying drawings:—

Figure 1 is a longitudinal sectional view of the preferred form of the ball mill.

Figure 2 is a transverse sectional view of the same.

50 Figure 3 is a perspective view of one of the sections of the lining.

Figure 4 is a longitudinal sectional view of a modified form of the mill.

Figure 5 is a perspective view of a lining

section which is used in the modified form of 55 the mill.

As illustrated in Figures 1, 2 and 3 of the drawings the ball mill comprises a body or drum 1 of the usual cylindrical form. This body is suitably supported and journaled for rotation, there being a gear wheel 2 and teeth 3 provided for rotating the drum in a usual manner. The material to be ground is introduced into the drum through the central inlet opening 4. The drum 1 is provided at its discharge end and at its peripheral portion with apertures 5 and adjustable gates 6 are located at the same end of the drum and may be moved over the apertures to regulate the quantity or flow 65 of the material through the apertures.

A renewable lining is provided for the drum of the mill and the said lining consists of sections 7 in the form of segments of a circle and these sections are arranged within the drum in sets which are placed end to end and the joints between the ends of one set of the sections are in staggered relation to the joints between the ends of the adjacent sets of sections as best illustrated in Figure 1 of the drawings.

The lining sections are provided at their inner sides with grooves 8 which extend longitudinally of the sections and the said sections are provided at their outer sides with feet 9 which are adapted to rest against the inner surface of the body of the drum whereby the body portion of the lining sections are spaced from the inner surface of the drum. The grooves 8 are adapted to receive the balls 10 of the mill. The sections 7 are further provided with slots 11 which are located at points between the grooves 8 and slots 12 which are located at the side edges of the sections.

When the material to be ground is fed into the drum 1 through the inlet opening 4 and the drum is rotated the balls 10 roll upon the material and break or disintegrate the same. This finer material gravitates 95 through the slots 11 and 12 and enters the space between the outer surfaces of the lining sections and the inner surface of the drum. The material then passes or flows out of the drum 1 and at the lower portion thereof and through the apertures 5. As the lining sections become unfit for use by reason of wear they may be individually re-

2
moved and new sections inserted in the drum and substituted in their stead. Therefore the degree to which the material is ground or reduced may be maintained uniform.

- 5 In the form of the invention as shown in Figures 4 and 5 the drum 1 is provided with a central discharge outlet 13 and the apertures 5 as shown and described in connection with the form illustrated in Figure 10 1 are eliminated. In the modified form the lining sections 14 are in the form of segments of a circle and they fit snugly against the inner surface of the body of the drum 1. These sections are provided with grooves 15 15 which receive the balls 16. In this form of the invention the material is introduced into the drum at one end and discharged at the opposite end. The balls 16 roll upon the material and reduce the same to fine particles and as the said balls are heavy enough 20

to sink in these particles, the particles are forced upwardly and pass out of the drum through the said discharge outlet.

In both forms of the invention a segmental lining section is employed and these 25 sections are provided with grooves for the reception of the grinding balls of the mill.

Having described the invention what is claimed is:—

30 In a mill lining a section in the form of a segment of a circle and having grooves at its inner side and feet at its outer side and having slots passing transversely through the same, some of the slots being located between the grooves and other of the slots 35 being located at the side edge portions of the segment.

In testimony whereof I affix my signature.

ERIC HEDBURG.
